GEOPHONE

Samuel E. Haggard, Houston, Tex., assignor to Mandrel
Industries, Inc., Menlo Park, Calif., a corporation of
Michigan

Filed Aug. 8, 1963, Ser. No. 76,156

Term of patent 14 years

(Cl. D72—1)

FIGURE 1 is an end elevational view of a geophone showing my new design;

FIGURE 2 is a side elevational view thereof; and

FIGURE 3 is a top plan view thereof.

The end of the geophone housing opposite that of FIG. 1 is a mirror image of FIG. 1 and the side of the geophone housing opposite that of FIG. 2 is identical to FIG. 2 except for the screw-clamp as shown in FIG. 1.

The fragmentary broken line showing of a connecting cable in FIGS. 2 and 3 is for illustrative purposes only.

I claim:

The ornamental design for a geophone, as shown and described.
